UNITED STATES PATENT OFFICE.

BENJAMIN W. CHANDLER, OF INDIANAPOLIS, INDIANA, ASSIGNOR, BY MESNE ASSIGNMENTS, TO LAYTON M. PARKHURST, OF CHAGRIN FALLS, OHIO.

DIE-CASTING MACHINE.

1,179,072.

Specification of Letters Patent. Patented Apr. 11, 1916.

Application filed August 10, 1911, Serial No. 643,270. Renewed September 12, 1914. Serial No. 861,473.

To all whom it may concern:

Be it known that I, BENJAMIN W. CHANDLER, a citizen of the United States, and a resident of Indianapolis, county of Marion, 5 and State of Indiana, have invented a certain useful Die-Casting Machine; and I do hereby declare that the following is a full, clear, and exact description thereof, reference being had to the accompanying drawings.

The object of this invention is to provide an improved die casting machine which may be quickly and easily operated by men unskilled in the art and adapted to make successively castings from different metals which require different treatment in melting them.

The feature of the invention lies in the quick introduction and the rapid expansion 20 or explosion of a gaseous or explosive mixture for forcing the molten metal from the containing crucible into the die, whereby no part of the metal will be deteriorated by oxidization as now results in those die casting machines using compressed air to force 25 the metal into the die. Along with the foregoing is the provision of means for mounting the crucible and insulating the same to prevent the radiation of heat with a resulting 30 cooling of the metal in the crucible. This construction makes use of a body oscillatably mounted in a supporting frame with means for clamping the die against the top of the body and in communication with the 35 crucible held within said body.

The nature of the invention will be understood from the accompanying drawings and the following description and claims.

In the drawings, Figure 1 is an end elevation 40 of the machine with parts broken away and showing the means for securing the die in the main frame. Fig. 2 is a vertical section on the line 2—2 of Fig. 1, showing the means for inverting the container pot and the means for supplying the explosive mixture to the crucible. Fig. 3 is a vertical section on the line 3—3 of Fig. 2, but showing the pot in an inverted position. Fig. 4 is a horizontal transverse section on the line 4—4

of Fig. 2, showing the means for supporting 50 the crucible in the pot. Fig. 5 is a vertical section on the line 5—5 of Fig. 2. Fig. 6 is a transverse section on the line 6—6 of Fig. 3, showing the gas passage in the side of the crucible. Fig. 7 is an elevation similar 55 to Fig. 1, with parts broken away and with the movable parts turned through an angle of approximately 170 degrees, and showing the gas valve open. Figs. 8 and 9 show the gas valves in elevation and plan, respectively.

In detail there is shown in the drawings a pair of A-shaped supporting frames 10 spaced apart at the lower end by the rods 11 and provided with bearings 12 at their 65 upper ends for trunnions 13 which oscillatably support a crucible container pot 14. Said crucible containing or holding pot 14 is by preference substantially U-shaped in cross section, as shown in Figs. 2 and 3, and has an inner wall 114 forming a chamber 15 and cast integral with and spaced apart from the outer wall to provide a dead space or insulating chamber 16 from which the air is exhausted through the pipe 117 extending 70 through the outer wall. The inner chamber wall 114 has a number of ribs 17, four being here shown, extending inwardly therefrom, and tapering slightly from bottom to top and are provided for the purpose of holding a crucible or melting pot 18. A nipple 19 screwed into the walls 14 and 114 of the crucible holder has a two way valve 20 mounted on the end and a pipe 21 is connected thereto for supplying a gaseous or other explosive mixture under pressure and introducing it into said chamber 15 when the valve 20 is opened. Pipe 21 has a check 80 valve 121.

A cover 22 fits upon the flat upper ring 90 of the crucible container 14 so as to make an air tight joint therewith and is secured thereto by bolts 23 extending through lugs 24 and 25 cast integral with the cover 22 and container 14, respectively, and has an inner or insulating chamber 26 from which the air is exhausted through the pipe 27. There is a downwardly tapering conical

opening 28 through the cover 22 not communicating with the insulating chamber 26 adapted to receive the conical shaped pouring spout 29, to be described later. Set 5 screws 30 extend through the inner and outer walls of said top 22 and have their ends flare button like for the purpose of holding the cover on the crucible.

The crucible 18 may be of any desired 10 construction, whether of vitrified material or of metallic material shell-lined with fire clay, excepting that it is provided with a small gas opening 31 through the wall above the level which the metal in the crucible will 15 assume when melted and the crucible is upright. Said crucible fits down within the chamber 15 and rests against and is secured by the inwardly extending ribs, before mentioned, and has a cap 32 adapted to fit over 20 its upper end which has an inwardly tapering conical hole in the central portion thereof to correspond with the opening 28 in the chamber 22. Said cover 32, when placed upon the crucible, is held down by the 25 screws 30.

The pouring spout 29, projects through the opening in the crucible cover 22 and, being conical in shape, may be driven into tight engagement with both the covers 22 30 and 32. The outer end of the pouring spout fits into a shouldered-portion in the die 33, said die being held thereon by means of a screw 34, having a hand wheel 35, keyed thereon and with the upper portion of the 35 screw extending through a frame 36 mounted on arms 37 which extend upwardly from the pot 14.

An upward extension 38 from one of the frames 10 carries a projection 39 which will 40 engage an L-shaped handle 40 of the two way valve 20 when the pot 14 has been revolved about 170 degrees and cause the opening of said valve. The air exhaust connections 117 and 27 are provided with pressure 45 gages 41 and valves 42.

The valve 20, before mentioned, has an L-shaped handle 40 with a spring 50 which is preferably coiled about one leg with one end inserted in a hole in the valve body and 50 with the other bearing against the other leg and tending to keep said valve in a closed position. The free end of said handle is preferably cut obliquely and has the outer part 52 connected to the main handle 40 by 55 the spring hinge 53.

The oscillating movement of the pot may be limited to an arc of 180 degrees by the pin 45 in the shaft 13 engaging a projection 46 from one of the bearings 12, as shown in 60 Figs. 2 and 5.

In operation a portion of the air in the insulating chambers 16 and 26 is exhausted in any desired way. The crucible 18 containing molten metal which has been melted else-

where in any desired way, is placed in the 65 container and the cover 32 placed on the crucible after which the cover 22 is placed upon the container 14 and secured thereon by means of the screws 23. The pouring spout 29 is then driven into place, the die adjusted on 70 the outer end of the spout and tightly secured thereon by turning the hand wheel 35 and causing the screw 34 to wedge against the upper part of the die. The pot 14 is then tilted toward the position shown in 75 Fig. 7, by turning the lever 43 on the shaft 13. After the pot has passed a horizontal position, the molten metal in the crucible 18 will flow through the spout 29 into the die 33 and when said pot approaches a vertical 80 position having turned through an arc, say of 170 degrees, the extension 52 of the handle 40 will be depressed by the projecting lug 39 on the arm 38 and cause the opening of the valve 20. The gas valve lever remains 85 in engagement with the projection 39 while the pot turns through an arc of approximately 5 degrees and on passing out of engagement with said lug the valve is quickly closed under the action of the 90 spring 50 on the valve stem. This closing is accomplished before the pot reaches the vertical position shown in Fig. 3. Thus a gaseous mixture under pressure will be suddenly introduced into the chamber 15 and, 95 passing through the hole 31 in the crucible 18, will meet with the molten metal contained therein, ignite and by the sudden increase of pressure resulting therefrom within the crucible the metal will be forced into 100 the die. This sudden introduction of the charge of gaseous mixture and the explosion thereof at a desired time to drive out the metal closely resembles the introduction and ignition of the explosive charge in the cylinder of an internal combustion engine where the piston is driven outwardly by the explosion. After the die has been poured the pot is turned back to its normal position, shown in Fig. 1, and in such passage 105 the lever extension 52 will again meet the lug 39, but the hinge 53 will allow it to pass by said lug 39 without actuating the valve and the spring in said hinge will cause the extension 52 to return to its normal position. After the machine has been moved to its normal position, the die may be removed from the machine by turning the hand wheel 35, thus releasing the die. It 110 will be readily understood that by this means of forcing the metal into the die none of the metal will be oxidized as now results in those die casting machines in which the metal is forced into the die by the use of compressed air.

My invention is not necessarily limited to the details of the construction which has been herein shown merely for the purpose 115 120 125

of illustrating the general nature of the invention. The main feature thereof being the discharge of the metal into the die by reason of the explosion or quick expansion of an explosive mixture in the crucible and also the employment of the heat insulating chamber within the pot or surrounding the crucible so that the crucible may be transferred to the pot after it has been heated and the metal therein melted in a separate furnace and yet the crucible be prevented from chilling for a reasonable length of time during which by successive die casting operations, a number of castings may be made from the same charge of metal in the crucible and until all of the metal therein has been used, without removing the crucible for reheating the metal therein.

I claim as my invention:

1. A die casting machine including a crucible with a suitable outlet, a die connected to the outlet, and means for introducing a charge of explosive gas into the crucible at the time of and for discharging the metal into the die.

2. A die casting machine including a crucible adapted to be tilted for discharging the metal into a die, and means for introducing a charge of explosive gas into the crucible at the time of such discharge.

3. A die casting machine including a crucible with an outlet at its upper end when upright, a die in connection with said outlet, means for tilting the crucible so the metal will flow into the die, and means for introducing a charge of explosive gas into the crucible when it is tilted.

4. A die casting machine including a crucible with an outlet at its upper end when upright, a die in connection with said outlet, means for tilting the crucible so the metal will flow into the die, a passageway into said crucible from a supply of explosive gas under pressure, a valve controlling said passageway, and means for opening said valve at the time of the discharge of the metal.

5. In apparatus of the character described, the combination of a crucible having an outlet, a die connected to the outlet, and means for introducing a charge of explosive gas into said crucible.

6. In apparatus of the character described, the combination of a crucible having an outlet, a die connected to the outlet, and mechanism for controlling the flow of metal through the outlet into the die, the said mechanism including means for introducing a charge of explosive gas into said crucible.

7. In apparatus of the character described, the combination of a crucible having an outlet, a die connected to the outlet, and means for controlling the flow of metal

through the outlet into the die, and means 65 for introducing a charge of explosive gas into said crucible.

8. In apparatus of the character described, the combination of a crucible having an outlet and mounted to move bodily 70 to control the flow of metal therethrough, a die connected with the outlet, means for moving said crucible whereby the metal therein flows into the die, and means for introducing a charge of explosive gas into the 75 crucible during movement thereof.

9. In apparatus of the character described, the combination with a support, of a casting apparatus comprising a crucible adapted to hold metal in a fluid state, a die, 80 a conduit leading from said crucible to said die, and means for introducing a charge of explosive gas into said crucible; means for rotatably supporting said casting apparatus on said support, and means carried by said support for controlling the supply of explosive gas during movement of said casting apparatus.

10. The combination of a crucible for holding metal, the said crucible having an 90 opening through its wall disposed above the level of the metal therein, a casing for supporting said crucible and provided with a recess into which the opening in the crucible leads, a die, a conduit leading from the crucible to said die, and means for introducing a charge of explosive gas into the recess in said casing.

11. In apparatus of the character described, the combination of a casing, a crucible mounted therein and adapted to hold the metal in a fluid state, devices interposed between the crucible and the casing for spacing the crucible therefrom to form a chamber, the said crucible being formed with an 100 opening above the level of the metal therein, a die, a conduit between the crucible and the die, and means for introducing a charge of explosive gas into the chamber between the crucible and said casing.

12. In apparatus of the character described, the combination of a casing mounted to move bodily, a crucible mounted therein and adapted to hold metal in a fluid state, devices interposed between the crucible and the casing for spacing the crucible therefrom to form a chamber, the said crucible being formed with an opening in its side wall above the level of the metal therein, when the crucible is in normal position, a die, a 110 conduit between the crucible and the die, means for moving said casing to cause the metal to flow from the crucible into said die, and means for introducing a charge of explosive gas into the said chamber during 120 movement of the casing.

13. In apparatus of the character described, the combination with a die, of a

casing open at its upper end, a top for said casing, a crucible mounted in said casing, a cover for said crucible, means carried by the casing top for clamping said cover in position, a conduit between said crucible and said die, means for moving said casing, and means for introducing a charge of explosive gas into said crucible.

In witness whereof I have hereunto affixed my signature in the presence of the 13 witnesses herein named.

BENJAMIN W. CHANDLER.
